UNITED STATES PATENT OFFICE.

ALBERT L. PIER, OF LOUISBURG, WISCONSIN.

RAIL-ANCHOR AND TIE-SPACER.

1,192,109.

Specification of Letters Patent. Patented July 25, 1916.

Application filed March 20, 1914, Serial No. 825,946. Renewed May 12, 1916. Serial No. 97,180.

To all whom it may concern:

Be it known that I, ALBERT L. PIER, a citizen of the United States, residing at Louisburg, in the county of Grant, and State of Wisconsin, have invented certain new and useful Improvements in Rail-Anchors and Tie-Spacers, of which the following is a specification.

In the operation of railroads, a serious cause of accidents is the spreading or other movement of the rails and also of ties, and the object of my invention is to firmly anchor the rails and also to adjustably space the ties and hold them in adjustably spaced positions and this without bolts and nuts.

The specification following taken in connection with the drawings accompanying the same and forming a part hereof will definitely point out and illustrate the construction I prefer, and the mode in which it operates.

Figure 1 is a perspective view of my device. Fig. 2 is a plan view of my device set between the ties. Fig. 3 is a perspective view of one of the members. Fig. 4 is a vertical section of the rail, and device attached to the rail. Fig. 5 is an enlarged perspective view of the plug and Fig. 6 is a side view of the key for locking the members together.

Like characters of reference denote corresponding parts in each of the figures.

Referring to the drawings, 2 is one of the body members and 4 is the other member. These members are provided with cogs or corrugations 5. These corrugations on each of the members are adapted to mesh or fit into each other and by these the device is adjusted longitudinally and the ends of the members brought into engagement with the ties to hold them at a given distance apart.

To the member 2 is secured a hook 8 adapted to engage the flange 10 of the rail, on one side. The hook is reinforced by the ribs 12 and to the member 4 is attached a plate 14 terminating in a hook 15 adapted to engage the opposite edge of the flange 10 of the rail. The hook 8 with the reinforcements 12 may be cast integral with the member 2 and the plate 14 and hook 15 may also be cast integral with the member 4.

Through the central portion of both members are rectangular slots 16 through which a rectangular plug 20 is inserted. The plug 20 is provided with a slot 22 in which a locking key 25 is inserted and locks the two

members 2 and 4 together and the hooks 8 and 15 rigidly in engagement with the flanges of the rail.

The inside of the plug 20 is roughened or corrugated at 23 and the key 25 is also roughened or corrugated at 32 to engage the corrugations 23 on the inside of the plug, whereby the key is kept from being jarred out or loosened.

The mode of operation is substantially as follows: The two hooks 8 and 15 of the members are brought into engagement with the flanges of the rail preferably about the middle of the rail and the corrugations 5 of each member are also brought into engagement with each other and the two members are adjusted so as to engage one side of two ties 9 and hold the two ties in the same position, and when they are in the position desired the plug 20 is placed in position through the slots 16 and the key 25 is forced down into the slot 22 with the corrugations 32 in engagement with the corrugations 23 in the plug and this draws the two members 80 rigidly together and the hooks 8 and 15 into rigid engagement with the flanges of the rail, and firmly holds them in the locked position. In this manner the rail is anchored and the ties are spaced and held in 85 the spaced position by engagement with the ends of the two members. They can also be adjusted so as to adapt them to rest between ties spaced at different distances apart.

Having now described my invention what I claim is:

1. In a device of the character described, two members each having one irregular surface adapted to be engaged by the irregular surface of the other, means for adjusting the members longitudinally to adapt them to engage ties set at different distances apart, means connected with the members for grasping a rail, and means for locking the two members together while in engagement with a rail and in their adjusted position between two ties.

2. In a device of the character described, two members provided with corrugations adapted to engage each other, means connected with the members for engaging the opposite edges of the flange of a rail, means for adjusting the members to adapt them to engage adjacent sides of ties spaced at different distances apart, and a plug and key 105 for locking the two members together in their adjusted position.

3. In a device of the character described, two members each provided with one uneven surface adapted to engage each other and restrain the movement of either, means for
- 5 adjusting the members longitudinally to adapt them to fill different spaces between the ties, hooks on each member for grasping the opposite edges of a rail and each member provided with a slot, a plug provided
- 10 with a slot and adapted to be inserted in the

slots in the members, and a key engaging the slot in the plug to lock the two members together and space the ties and anchor the rails.

In testimony whereof I affix my signature 15
in presence of two witnesses.

ALBERT L. PIER.
